UNITED STATES PATENT OFFICE.

EDWARD H. LAWRENCE, OF CAMERON, WEST VIRGINIA.

INLET-VALVE.

1,287,355.

Specification of Letters Patent. Patented Dec. 10, 1918.

Application filed November 16, 1917. Serial No. 202,335.

To all whom it may concern:

Be it known that I, EDWARD H. LAWRENCE, a citizen of the United States, a resident of Cameron, county of Marshall, and State of West Virginia, (whose post-office address is Cameron, W. Va.,) have invented certain new and useful Improvements in Inlet-Valves; and I do hereby declare the following to be a full, clear, and exact description of the invention, such as will enable others skilled in the art to which it appertains to make and use the same.

This invention relates to an inlet valve, which is particularly adapted for use in connection with tanks into which the flow of the fluid is automatically regulated.

An object of the invention resides in the provision of a valve by which the flow of the fluid will be regulated and which will be positive in its action so as to open and close at the proper time.

Furthermore it is an object of the invention to so construct the device that it will be exceedingly simple and consequently its liability of becoming inoperative will be reduced to a minimum.

A still further object of the invention resides in so constructing the device that the pressure of the fluid tends to seat rather than unseat the valve.

With these and other objects in view, such as will appear as my description progresses, my invention comprises the combination and arrangement of parts, as set forth in and falling within the scope of the appended claims.

In the drawing:

Figure 1 is a sectional view of a tank showing a valve constructed in accordance with my invention located therein, said valve being shown closed and in elevation.

Fig. 2 is an enlarged fragmental sectional view showing the valve unseated, and

Fig. 3 is an enlarged fragmental sectional view on line 3—3 of Fig. 1.

In the drawings I have represented a tank 1, in which the water level is indicated at 2.

Extending up through the bottom of the tank is an inlet tube 3, the joint between the tube and the tank being made water tight by the gasket 4 and nut 5. This tube 3, is bent back upon itself, as illustrated in Fig. 1, substantially into the form of a goose neck. The end of the tube is bent outwardly at 6, and is provided with a reduced open end 7. The reduction of the diameter of the

tube results in the provision of an internal shoulder 8 adjacent to the open end for the purpose which will later appear. This tube 3 is made of resilient material so that the tendency of the open end of the tube is to move away from the main body of the tube, that is to say, from that portion which is connected directly to the tank.

Extending from this latter portion of the tube adjacent to the point where it is connected to the tank, is a bracket 9, which is provided with an upwardly extending portion 10 having an aperture 11 extending therefrom. This portion 10 carries a casting 12 which is attached by means of a thumb screw 13, and which is provided with a valve seat 14 of any suitable material, such for instance as rubber. The thumb screw 13 engages the rear face of this seat 14 so as to back the same up and maintain it in the proper position to be engaged by the valve at the open end of the tube 3.

The casing 12 also is provided with an arm 15, to which is pivoted at 16, a lever 17. On the end of this lever 17 a heavy float 18 is adjustably secured at 19. The opposite end of the lever is provided with a bill 20, which extends downwardly and into a notch 21, formed between a pair of projections 22 on the upper side of the free end 6 of the tube 3.

When the parts are in the positions illustrated in Fig. 1 of the drawings, the valve is closed. The effect of the heavy float 18 is destroyed because of the fact that it is buoyed by the fluid in the tank. The valve at the end of the tube 3 is therefore in engagement with the valve seat. This engagement is brought about by the resiliency of the tube itself and also by the pressure of the fluid within the tube, since the tube, being bent, tends to straighten out under the action of the pressure within the same and since this straightening out of the tube forces the valve into engagement with the valve seat. Furthermore, the lever 17 operates to seat the valve as the float 18 moves upwardly to its final position. Of course, the flow of the fluid from the valve or the open end of the tube, produces a certain amount of back pressure since the out going fluid impinges the valve seat 14. The tendency of this back pressure to prevent the valve from seating is overcome, however, by the presence of the shoulder 8 within the tube, as the pressure within the tube acts

against this shoulder and forces the valve end or open end of the tube against the seat. Thus the effectiveness of the resiliency of the tube, the pressure within the tube and the float 18 is not depreciated by the back pressure developed.

As the water is withdrawn from the tank and the level thereof lowered, the float 18 will drop, and since the weight of this float 10 is sufficient to overcome the resiliency of the tube and the effect of the pressure within the same, the valve or open end of the tube will be unseated and the fluid permitted to flow into the tank until the effect of the float is 15 destroyed.

I have illustrated only one form of my invention, but this form was merely selected for the sake of convenience of illustration, as it is quite obvious that numerous other forms 20 may be produced without departing from the spirit of the invention or without exceeding the scope of the claims. I therefore do not wish to be limited to the particular embodiment illustrated, but claim such latitude of construction as is permitted by the 25 claims.

What I claim is:—

1. An inlet valve including a resilient inlet tube carrying a valve, a valve seat, 30 said tube being operative to seat the valve, and automatically operable means for unseating the valve against the resiliency of the tube.

2. An inlet valve including a resilient inlet tube carrying a valve, a valve seat, said tube being operative to seat the valve, and gravity actuated means for unseating the valve against the resiliency of the tube.

3. An inlet valve including a resilient inlet tube carrying a valve, a valve seat, 40 said tube being operative to seat the valve, and a float for unseating the valve against the resiliency of the tube.

4. An inlet valve including a valve seat, 45 and a bowed, resilient inlet tube having a valve thereon arranged to engage the valve seat, said tube being operative to seat the valve.

5. An inlet valve including a valve seat, 50 a bowed, resilient inlet tube having a valve thereon arranged to engage the valve seat, said tube being operative to seat the valve, and means to unseat the valve.

6. An inlet valve including a resilient inlet tube having an open end movable 55 under the influence of the resiliency of the tube, and a seat against which such open end is adapted to abut.

7. An inlet valve including a resilient

inlet tube having an open end movable 60 under the influence of the resiliency of the tube, a seat against which such open end is adapted to abut, and means for moving the end of the tube to unseat the open end.

8. An inlet valve including a resilient inlet tube having an open end movable under 65 the influence of the resiliency of the tube, a seat against which such open end is adapted to abut, and gravity actuated means for moving the end of the tube to unseat the 70 open end.

9. An inlet valve including a resilient inlet tube having an open end movable under 75 the influence of the resiliency of the tube, a seat against which such open end is adapted to abut, said tube having an internal pressure receiving shoulder adjacent to the open end thereof.

10. An inlet valve including an inlet tube having an open end, a seat against which 80 said open end is adapted to abut, and float actuated means for moving the open end of the tube toward said seat, said tube having an internal pressure receiving shoulder for assisting in said movement of the end of 85 the tube.

11. An inlet valve including an inlet tube having an open end, a seat against which 90 said open end is adapted to abut and against which the fluid flowing from the tube impinges, the tube being provided with means for balancing the pressure developed by the impinging of the fluid against the seat and which tends to prevent the seating of the open end of the tube.

12. An inlet valve including a resilient inlet tube having an open end, a seat against which the said open end is adapted to abut, and float actuating means for moving the open end of the tube toward said seat, said tube having an internal pressure receiving shoulder for assisting in said movement of the end of the tube, the resiliency of the tube 100 also assisting in said movement.

13. An inlet valve including an inlet tube 105 having an open end, a seat against which said open end is adapted to abut, and against which the water flowing from the tube impinges, and means for moving the end of the tube into engagement with said seat, the 110 tube being provided with means for balancing the pressure developed by the impinging of the water against the seat and which tends to prevent the seating of the open end of the tube.

In testimony whereof I affix my signature.

EDWARD H. LAWRENCE.
